FIREPLACE GUARD SCREEN

William O. Dailey, Portland, Oreg.

Application March 5, 1932. Serial No. 596,933

8 Claims. (Cl. 126—202)

This invention relates to means for screening any type of open fireplace, and more particularly to such means as may be readily associated with a fireplace that is in the course of construction; 5 or which may be attached to and removed from a fireplace already constructed; and this invention especially relates to fireplace guard screens constructed in such a manner that the screens may be raised or lowered in curtain fashion and 10 can be hidden from view when desired.

It has been and is undoubtedly the present custom to place in front of an open fireplace an independent guard screen, usually unsightly, which must be carried into and out of position 15 and which takes up a lot of space in front of the fireplace. I am also aware of the fact that there are a number of fireplace guard screens adapted to be associated with or attached to an open fireplace whose purposes are to eliminate the disadvantages of independent guard screens.

The particular object of my invention is to overcome not only the disadvantages of the independent guard screens, but also those disadvantages which have become apparent in the application of the guard screens heretofore invented. I accomplish this object by providing a 25 guard screen that is inexpensive, simple and durable in construction and that can be quickly and easily manufactured and installed without detriment or change to the fireplace.

Experience has shown that any screening means placed before a fireplace will prevent a substantial portion of the heat from entering the room where the fireplace is located and consequently the greater portion of the heat is dissipated through the chimney. It is also a well known fact that when the screening means are entirely removed from the front of the fireplace, blasts of heat enter the room to the discomfort 35 of those who enjoy sitting nearby. It is my primary purpose to overcome these salient disadvantages by the application of my improved fireplace guard screen which includes independent sectional screen elements whose removal or adjustment allows one to control the volume of heat 45 that may enter into the room and to determine the channel through which the heat may enter.

One object of my invention is to construct the fireplace guard screen in such a manner that 50 the screen portion will be invisible from the outside of the fireplace when not in use.

A further object of my invention is to provide a fireplace guard screen which may be readily manipulated to control and regulate the draft, 55 that will prevent sparks from flying out of the

fireplace, and that will easily lend itself to adjustment so that the screen elements may be moved into or removed from their positions without hindering the operation of the remaining structure. 60

A still further object of my invention is to provide elevating and lowering mechanism for a plurality of independent screen elements that give the appearance of a single screen guard when each of them are in their full lowered position. 65

Still another object of my invention is to provide a plurality of screen elements which are adapted to overlap each other when in full lowered position and present the appearance of a 70 single screen when in such position.

Another object of my invention is to provide certain novel operating and elevating mechanisms which co-operate with certain novel rack elements that are adapted to hold a plurality of independent screen units in overlapping position. 75

A further object of my invention is to provide a plurality of independent screen units that may be easily removed for repair, for cleaning, or for any other purpose without effecting the 80 operation of the whole structure.

For a full understanding of my invention and for other objects and advantages to become apparent and readily understood and for obtaining knowledge of the nature and characteristic features of the invention from the details of construction, reference is to be had to the following description and accompanying drawings in which: 85

Figure 1 is a front elevation of a fireplace provided with guard screens made in accordance with my invention. 90

Figure 2 is a sectional front elevation of my invention showing various elements used in the operation of my fireplace guard screens. 95

Figure 3 is a sectional side view of my invention taken on line 3—3 of Figure 2 looking in the direction indicated and showing the relation of the various parts to each other. 100

Figure 4 is a top plan view of my invention taken on line 4—4 of Figure 1 looking in the direction indicated and illustrating the position of the means for engaging the operating means.

Figure 5 is a perspective side view of one of the elevating elements showing the serrations disposed therein. 105

Figure 6 is a sectional side elevation of the invention taken on line 6—6 of Figure 2 looking in the direction indicated and illustrating the 110

position of the screen portions with respect to each other.

Figure 7 is a front elevation of another type of fireplace provided with screens made in accordance with my invention.

Figure 8 is a sectional front elevation of the invention showing some of the screen elements in raised position and being maintained in that position by the elevating elements.

Figure 9 is a fragmentary, sectional, side view of the invention taken on line 9—9 of Figure 7 looking in the direction indicated and showing the manner of attaching the frame to the fireplace and showing the position of the drums in the frame.

Figure 10 is a fragmentary front view of the invention taken on line 10—10 of Figure 9 looking in the direction indicated and showing the means for locking the crank to the frame.

Figure 11 is a fragmentary front view of one of my screen elements shown in a frame condition.

Corresponding and like parts are referred to in the following description and indicated in all the views of the drawings by the same reference characters.

In Figure 1 there is shown the front of an ordinary fireplace 1 to which my device may be removably attached or fixedly secured. The frame 2 is positioned in front of the open portion of the fireplace and has sides 3 and 4 that extend downwardly. Upon the upper portion of the frame 2 are a number of openings 5 adapted to be engaged by locking pawl 6 that extends downwardly from handle 7. The handle 7 has an opening 8 therein into which safety catches 9 and 10 fit. The safety catches are disposed at each end of the top portion of the frame which are also adapted to hold the handle 7 relative to the frame 2.

Disposed in spaced relationship with the sides 3 and 4 of the frame are racks 11 and 12. These racks are hidden from view within the frame and have a plurality of steps 13 disposed therein. The steps of one of the racks are directly aligned with the corresponding steps of the other rack.

A plurality of screen elements 14 are removably disposed upon the stepped racks 11 and 12. Each of the screen elements 14 have reinforced elements 15 disposed therein. Said reinforced elements have arms 16 and 17 extending beyond the sides of the screen elements in order to permit the placement of the screen elements upon the stepped racks. The screen elements 14 may be made as shown in Figure 11 wherein a frame 18 extends around the screen portion and has arms 19 extending outwardly from the upper portion and at each side thereof that perform the identical functions that arms 16 and 17 perform.

The vertical distance between steps in each of the racks is slightly less than the height of each of the screen elements. The purpose of this arrangement is to permit the screen elements to overlap when resting upon the steps in the racks and to intimately contact each other while in such an overlapping position and thereby present the appearance of a single screen.

Guiding wells 20 and 21 are formed between the sides of the frame 2 and each of the racks 11 and 12. Elevators 22 and 23 are slidably disposed within the guiding wells. Each of the elevators has a back 24, a base 25 and a front 26. Serrations or grooves 27 are disposed upon the top surface of the front 26. The front 26 of each of

the elevators 22 is substantially of the same height as the height of each of the screen elements and the serrations or grooves 27 are directly aligned with the corresponding steps in the racks so that when the elevators are raised, each of the screen elements, disposed upon their respective steps, will be vertically raised and held upon the elevators in the serrations or grooves intended for them.

Journal bearings 28 and 29 are disposed near the top and at one side of the frame 2 and shaft 30 is disposed therein. Pulleys 31 and 32 are disposed upon the shaft 30. On the oppositely disposed side of the frame is disposed journal bearings 33 and 34 having shaft 35 disposed therein upon which pulley 36 is secured.

Cable or chain 37 is secured to elevator 32 and cable or chain 38 is secured to elevator 33. Cable or chain 37 rides upon pulley 36 and has its oppositely disposed end secured to the handle 7. Cable or chain 38 rides over pulley 36 and under pulley 31 and has its free ends secured to the handle 7. By this arrangement it is apparent that both elevators are raised simultaneously by pulling upon the handle 7; and as the elevators 22 and 23 are moved upwardly, they raise the screen elements 14 one at a time.

In Figures 7 to 10 inclusive I have shown a somewhat different embodiment of my invention in which 39 designates the front portion of a fireplace upon the front of which frame 40 is disposed. Frame 40 has sides 41 and 42 under which racks 43 and 44 are disposed which are constructed in the same manner as the racks that have been heretofore described in detail.

The elevators 45 and 46 are also identical in structure to the elevators 22 and 23. The only substantial difference between this embodiment and the one heretofore described is in the manner of raising or lowering the elevators. This is accomplished by having shaft 47 journal within the upper portion and upon one side of the frame. Pulley 48 is disposed about shaft 47. Shaft 49 is journaled within the oppositely disposed side of the frame 40. Pulley 50 is disposed about shaft 49.

Drum 51 is rotatably disposed within journal bearings 52 and 53 disposed centrally of and within the upper portion of the frame 40. Shaft 54 extends through the frame and has attached thereto disc 55. Disc 55 has handle 56 secured near its outer periphery. Handle 56 has locking lug 57 normally protruding inwardly and through the disc.

A plurality of grooves 58 and 59 are disposed within the upper portion of the frame 40 which are in alignment with the locking lug 57. Cable 60 is secured to elevator 45 and rides over pulley 48 and over drum 51 to which it has its free end attached. Cable 61 is secured to elevator 46 and rides over pulley 50 and under drum 51 to which it has its free end attached.

In Figure 9 is shown the manner of attaching the frame 40 to the fireplace 39. This may be accomplished by any type of fastening means, as by a bolt 62, that has a lug 63 at its one end and is threaded at its other end. A second lug 64 is disposed about the bolt 62 and a threaded nut 65 is disposed about the threaded end of the bolt 62. By the application of pressure lugs 63 and 64 engage with frame 40 and fireplace 39 respectively.

From the foregoing description it will be readily seen that I have produced such a fireplace guard

screen as will substantially fulfill the objects of the invention set forth herein.

While the invention has been described with considerable particularity in order that the best 5 form of the invention may be readily understood, the invention is not to be considered limited to the specific details hereinbefore set forth, since changes may be made in many of the details of construction without departing from the true 10 spirit of the invention as defined in the appended claims. Having thus described my invention, what I claim is:

1. A fireplace guard screen comprising a frame, uniformly stepped racks disposed at each side of 15 the frame, said racks being disposed in spaced relationship with the sides of the frame to form wells therebetween, an elevator slidably disposed in each of the wells, said elevators having a plurality of uniformly spaced grooves directly 20 aligned with the steps in the racks and with the grooves in the other of the elevators, a plurality of screen elements normally disposed upon the stepped racks, and raising and lowering means 25 secured to the elevators for simultaneously moving said elevators in the same direction, said elevators upon vertical movement contacting the said screen elements to successively either raise or lower them.

2. A fireplace screen comprising a frame having 30 side portions, a vertical, uniformly stepped rack adjacent each side portion, a plurality of independent screen sections disposed in overlapping relation between said racks, being supported by the steps thereon and having rod portions projecting 35 therebeyond, means adjacent each side portion arranged for simultaneous vertical movement for successively contacting said rods to raise and lower said sections upon a like movement of said means, and means for operating 40 said first means.

3. A fireplace screen comprising a frame having side portions, a vertical uniformly stepped rack disposed adjacent each side portion, a 45 plurality of independent screen members supported by the racks and disposed in overlapping relation therebetween, means adjacent each side portion arranged for simultaneous vertical movement for successively raising and lowering said members upon a like movement of said means, and means for operating said first means.

4. A fireplace screen comprising a frame having side portions, uniformly stepped means adjacent each side portion, a plurality of screen sections disposed in overlapping relation between said stepped means, being supported by the steps thereon and having rod portions projecting 55 therebeyond, means adjacent each side portion arranged for simultaneous vertical movement for successively contacting said rods to raise and lower said sections upon a like movement of said elevators, said elevators having 60 therein uniform serrations which are directly aligned with the steps in the rack, and means for operating said elevators.

means, and means for operating said second means.

5. A fireplace screen comprising a frame having side portions, vertical, uniformly stepped means adjacent each side portion, a plurality of independent screen elements disposed in overlapping relation between said means, being supported by the steps thereon and having portions projecting therebeyond, elevating members slidably disposed between each side portion and each stepped means and arranged for simultaneous vertical movement for successively contacting said portions to raise and lower said screen elements upon a like movement of said elevating members, and means for operating said elevating members. 80

6. A fireplace screen comprising a frame having side portions, uniformly stepped means adjacent each side portion, a plurality of screen members disposed in overlapping relation between said means, being supported by the steps thereon and having arm portions projecting therebeyond, means adjacent each side portion arranged for simultaneous vertical movement for successively contacting said arms to raise and lower said members upon a like movement of said means, said second means having therein serrations which are directly aligned with the steps in the said first means, and means for operating 95 said second means.

7. A fireplace screen comprising a frame having side portions, vertical, uniformly stepped means adjacent each side portions, a plurality of independent screen sections disposed in overlapping relation between said means, being supported by the steps thereon and having rod portions projecting therebeyond, and means adjacent each side portion arranged for simultaneous vertical movement for successively contacting said rods to raise and lower said sections upon a like movement of said means, said second means having serrations therein which are directly aligned with the steps in the said first means. 100

8. In a device of the class described the combination of a frame having side portions, a vertical uniformly stepped rack adjacent each side portion, the side portions and their respective racks forming guidewells therebetween, a plurality of independent screen sections disposed in overlapping relation between the racks, being supported by the steps thereon and having rod portions projecting therebeyond, an elevator disposed in each guidewell arranged for simultaneous vertical movement for successively contacting said rods to raise and lower said sections upon a like movement of said elevators, said elevators having 120 therein uniform serrations which are directly aligned with the steps in the rack, and means for operating said elevators. 125
